UNITED STATES PATENT OFFICE

2,277,513

ELECTRIC APPARATUS FOR TREATING EMULSIONS

Harold C. Eddy, Los Angeles, Calif., assignor, by
mesne assignments, to Petrolite Corporation,
Ltd., Wilmington, Del., a corporation of Delaware

Original application January 26, 1937, Serial No.
122,470. Divided and this application July 11,
1938, Serial No. 218,681

6 Claims. (Cl. 204—302)

My invention relates to a novel electric apparatus for treating emulsions which finds utility in the electric treatment of emulsions regardless of the manner of forming these emulsions or the particular constituents thereof. For instance, while the electric treater herein-disclosed has been found to be very effective in a desalting process such as exemplified in my Patent No. 2,182,145, infra, it is also generally applicable to the dehydration of crude oil emulsions or other emulsions, and it is an object of the present invention to provide a novel apparatus for electrically treating emulsions.

It is a further object of the present invention to provide an electric treater including an upper and a lower live electrode with an intermediate live electrode structure, the emulsion being introduced through a grounded means.

Further objects and advantages of the present invention will be apparent to those skilled in the art from the following description.

Referring to the drawing:

Fig. 1 is a vertical sectional view of the preferred form of electric treater.

Fig. 2 is an enlarged fragmentary view of the upper and intermediate electrode structure.

Fig. 3 is a sectional view of the emulsifying valve discharging into the electric field.

In Fig. 1, the emulsion is forced under pressure through a pipe 86 leading to the electric treater 87. This pipe is connected to a distributor means 105 disposed in the electric treater 87 and best shown in Figs. 1 and 3.

Referring to Fig. 3, it will be noted that the pipe 86 carries a primary member 106 which cooperates with a secondary member 107 in forming an annular discharge passage 108. It is often possible to movably mount the secondary member 107 resiliently moving it toward the primary member 106 so that the size of the annular discharge passage 108 is dependent upon the quantity of the mixture moving through the pipe 86. In accomplishing this result, the secondary member 107 may be provided with a pin 108a guided in a spider 109 and carrying a spacer 110 at its lower end. A compression spring 111 is disposed between the spider 109 and the spacer 110 and serves to resiliently move the secondary member 107 downward. When no liquid is moving through the pipe 86, the members 106 and 107 will be in contact, but as soon as a flow is established, the pressure will force the secondary member 107 upward a slight distance to open the annular discharge passage 108 in degree proportional to the quantity of liquid to be discharged.

The details of one type of treater 87 which I have found particularly advantageous are best shown in Fig. 1. Referring to this figure, this treater 87 provides a tank 115 including a top

member 116 and a bottom member 117, this tank being grounded as indicated by the numeral 118.

Suspended from insulators 119 is a live electrode means, shown as including an upper live electrode 120 and a lower live electrode 121, the latter being supported from and electrically connected to the upper live electrode 120 by rods 122.

Suspended from an insulator 124 and positioned 10 between the upper and lower live electrodes 120 and 121 is an intermediate live electrode structure 125 respectively cooperating with the electrodes 120 and 121 in providing an upper treating space 126 and a lower treating space 127. I 15 prefer to form the intermediate electrode structure 125 of two electrodes 128 and 129 connected by a support 130.

The electrodes 120, 121, 128, and 129 are preferably formed of interstitial character. A form 20 of construction which I have found particularly desirable is illustrated in Figs. 1 and 2. Referring to the electrode 120, this electrode is shown as including a plurality of inner and outer rings 132 and 133 between which extend rods or pipes 134. Pins 136 depend therefrom and carry a plurality of concentric rings 131, each of which provides a lower edge 138 adjacent which the electric field is very concentrated.

The electrode 128 is similarly formed with rods 30 or pipes 140 extending outward from a support 141 and carrying upward-extending pins which, in turn, mount a plurality of concentric rings 143. The rings 143 are preferably disaligned from the rings 131 so that the most intense portion 35 of any electric field established in the treating space 126 is inclined as indicated by dotted lines 144 in Fig. 2. Such an edge-to-edge field is very effective.

The electrode 129 is formed similar to the electrode 128 and provides downward-extending rings 150. Similarly, the electrode 121 is formed similar to the electrode 130 and provides upward-extending rings 151 so that a field is established in the treating space 127 similar to that previously described in the treating space 126. I 45 have found it preferable to form the electrodes 121 and 129 of smaller diameter than the electrodes 120 and 128.

This type of electrode structure presents a 50 minimum impedance to gravitational separation in the tank 115, the rings and the supporting means therefor covering only a small fraction of the total cross-sectional area of the tank. Further, the interstitial nature of these electrodes permits free communication between the electric field and facilitates rapid removal of coalesced water masses therefrom.

Various means may be utilized for energizing the electrodes to establish electric fields in the 55 treating spaces 126 and 127. In the construc-

tion illustrated, all of these electrodes are live, the only grounded portions being the tank and the emulsifying distributor means 105, the latter discharging directly into the treating space 127 to move the emulsion outward therein and successively through the edge-to-edge fields. By proper design of the electrical system, the potential between the intermediate electrode structure 125 and the electrodes 120 and 121 can be made much higher than the potential between any of the live electrodes and ground. In Fig. 1, such a system is shown as including two transformers 160 and 161 connected in additive relation. In this connection, one terminal of each secondary winding is grounded as indicated by the numeral 162, the high tension terminal of the transformer 161 being connected by a conductor 163 to the intermediate electrode structure 125, and the high tension terminal of the transformer 160 is connected by a conductor 164 to the upper and lower live electrodes 120 and 121. Suitable switches and control means limiting the current to the primaries of these transformers may be utilized, such means being well known in the art of electric dehydration of emulsions.

Assuming, for instance, that each transformer develops a potential of 12,000 volts, the potential across the upper treating space 126 will be 24,000 volts, as will also the potential across the lower treating space 127. However, the potential between the emulsifying distributor means 105 and the electrode 129, or the electrode 121, will be only 12,000 volts. Use of such a system tends to prevent short-circuiting to the distributor means 105 and also permits introduction of the emulsion directly into a field of high voltage. I believe it to be new to utilize upper and lower live electrodes with an intermediate live electrode in this capacity.

The action of the electric fields is to coalesce the dispersed water particles of the emulsion into masses of sufficient size to gravitate from the oil. Thus, after the treater has been in operation for a period, the upper end of the tank 115 will contain the treated oil and the lower end of the tank will contain a body of separated water. These bodies will separate at a rather definite surface or level, indicated in Fig. 1 by the numeral 170. It is desirable to rather definitely control this level to prevent grounding of the electrode 121. In this connection, it will be apparent that an electric field will be established in an auxiliary treating space 171 between the lower live electrode 121 and the body of water in the bottom of the tank 115. If the level 170 is carried too high, this auxiliary field may short out. However, with proper control of the level 170, this auxiliary field can be utilized to further treat the settling water particles and can be used to break an inverse-phase or reverse-phase emulsion as will be hereinafter described.

To control the water level in the tank 115, I have shown an automatic system including a pipe 175 communicating with the upper part of the tank 115 and a pipe 176 communicating with a water draw-off pipe 177 which opens on the lower end of the tank 115. The pipes 175 and 176 communicate with a float chamber 178 in which the oil and the water are in surface contact at a level corresponding to the level 170. A properly balanced float 179 is disposed in the chamber 178, being so formed as to float in water and sink in oil. The position of this float will thus change in response to changes in the level 170. This float may be pivoted on a pin 180 75

connected to an arm 181 which is connected to a valve 182 in the pipe 177 by any suitable means, such as a link 183 connected to an arm 184 of the valve 182 pivoted at 185 and operatively connected to the stem 186 of this valve. If the water level rises, the valve 182 will thus be opened a further distance to drain additional quantities of water from the tank 115 and thus maintain the water level constant. Various other systems for controlling the position of this water level may be utilized without departing from the spirit of the present invention.

The treated oil moves from the upper end of the tank 115 through a pipe 200, the flow being controlled by a valve 201 which, in turn, assists in controlling the pressure in the tank 115. It is usually preferable to introduce the emulsion directly into the electric field rather than to introduce the emulsion into the tank 115 at a point spaced from the field, allowing the emulsion to gravitate thereto. Sludging tendencies are almost completely eliminated by a direct introduction into the electric field.

Usually, though not invariably, it is desirable 25 to carry a slight pressure in the electric treater 87, this pressure being from atmospheric pressure to approximately 50 lbs./sq. in. or above.

This application is a division of my application Serial No. 66,404, filed February 29, 1936, and its 30 continuation-in-part Serial No. 122,470, now Patent No. 2,182,145.

Various other changes and modifications can 35 be made without departing from the spirit of the present invention as defined by the appended claims.

I claim as my invention:

1. In combination in an electric treater including a tank: an upper live electrode in said tank; a lower live electrode in said tank; an intermediate live electrode structure between said upper and lower live electrodes and cooperating therewith in defining upper and lower treating spaces; means for impressing a potential difference between said intermediate electrode structure and said upper and said lower live electrodes; introduction means grounded to said tank for discharging a fluid to be treated radially into said lower treating space at a position intermediate the upper and lower ends thereof; and means for insulating said upper, lower and intermediate electrode structures from said tank and grounded introduction means whereby auxiliary electric fields are set up between said grounded introduction means and the live electrodes bounding said lower treating space and between the tank and each of the electrodes.

2. In combination in an electric treater including a tank: an upper live electrode of interstitial character in said tank; a lower live electrode in said tank and providing a central opening; means for electrically connecting said lower live electrode to said upper live electrode and for supporting said electrodes as a unit insulated from said tank; an intermediate live electrode structure of interstitial character between said upper and lower live electrodes; means for supporting said intermediate live electrode structure in spaced relationship with said upper and lower live electrodes to form upper and lower treating spaces and for insulating said intermediate live electrode structure from said tank; means for impressing between said intermediate live electrode structure and said upper live electrode and between said intermediate live electrode structure and said lower live electrode a potential dif-

ference higher than the potential difference between said upper, lower, or intermediate electrode structures and ground; and an emulsion-distributing means grounded to said tank and extending upward through said central opening of said lower live electrode and providing an annular orifice for directing emulsion radially outward between said lower live electrode and said intermediate electrode structure.

3. In combination in an electric treater including a tank: an upper live electrode of interstitial character in said tank and insulated therefrom, said electrode extending horizontally across a substantial portion of the space inside said tank; a lower live electrode insulated from said tank and of substantially smaller size than said upper live electrode and disposed below said upper live electrode; an intermediate electrode structure between said upper and lower live electrodes and providing an interstitial upper portion spaced below said upper live electrode to form an upper treating space and a lower portion spaced above said lower live electrode to form a lower treating space, said upper portion being of a size commensurate with that of said upper live electrode and said lower portion being of a smaller size commensurate with that of said lower live electrode; means for introducing an emulsion into said lower treating space; and means for establishing electric fields in both said upper and said lower treating spaces and for maintaining a difference in potential between said tank and each of said upper and lower live electrodes.

4. In combination in an electric treater including a grounded tank, the upper portion of which provides a space for oil and water undergoing gravitational separation and the lower portion of which provides a space for a body of separated water: an upper live electrode in said upper portion of said tank; means for suspending said upper live electrode in said upper portion of said tank, said means including insulating means for insulating said upper live electrode from said tank; rod means formed of electrically conducting material, said rod means being supported by said insulating means and electrically connected to said upper live electrode and extending downward to a position below said upper live electrode; a lower live electrode electrically connected to and supported by said rod means at a position below said upper live electrode but above the surface of said body of water whereby said rod means electrically connects said lower live electrode to said upper live electrode; an intermediate electrode structure; means for supporting same between said upper and lower electrodes to cooperate therewith in defining upper and lower treating spaces, said supporting means including means for insulating said intermediate electrode structure from said tank; means for establishing between said intermediate electrode structure and said upper and lower live electrodes a potential difference substantially greater than the potential difference between any of these electrode structures and the grounded tank thereby establishing also a field-establishing potential difference between said lower live electrode and said body of water; and means for delivering emulsion to said lower treating space.

5. In combination in an electric treater including a grounded tank, the upper portion of which provides a space for oil and water undergoing gravitational separation and the lower portion of which provides a space for a body of separated water: an upper live electrode in said upper por-

tion of said tank, said electrode being of interstitial character and providing an opening; means for suspending said electrode in the upper portion of said tank, said means including insulating means for insulating said electrode from said tank; rod means formed of electrically conducting material, said rod means being supported by said insulating means and electrically connected to said upper live electrode and extending downward to a position below said upper live electrode; a lower live electrode of interstitial character insulated from said tank and providing an opening and electrically connected to and supported by said rod means at a position below said upper live electrode but above the surface of said body of water whereby said rod means electrically connects said lower live electrode to said upper live electrode; an intermediate electrode structure of interstitial character between said upper and lower live electrodes and cooperating respectively therewith in defining upper and lower treating spaces; means extending downward through the opening of said upper live electrode for suspending said intermediate electrode in position; an emulsion distributor means grounded to said tank and extending upward through the opening of said lower live electrode and providing orifice means discharging into said lower treating space; and means for establishing electric fields in said upper and lower treating spaces and between said lower live electrode and said body of water in the lower end of said tank.

6. In combination in an electric treater including a grounded tank the upper portion of which provides a space for oil and water undergoing gravitational separation and the lower portion of which provides a space for a body of separated water: an upper live electrode of interstitial character in said tank, said electrode extending horizontally across a substantial portion of the space inside said tank and providing a central opening; means for suspending said electrode in the upper portion of said tank, said means including insulating means for insulating said electrode from said tank; rod means formed of electrically conducting material, said rod means being electrically connected to and extending downward from the periphery of said upper live electrode and providing inward-extending portions positioned below said upper live electrode; a lower live electrode of substantially smaller size than said upper live electrode and electrically connected to said inward-extending portions whereby said rod means electrically connects said lower live electrode to said upper live electrode; an intermediate electrode structure between said upper and lower electrodes and providing an interstitial upper portion spaced below said upper live electrode to form an upper treating space and a lower portion spaced above the lower live electrode to form a lower treating space, said upper portion being only slightly smaller in size than said upper live electrode to prevent short-circuiting to said rod means and said lower portion being of a size smaller than said upper portion and of a size commensurate with that of said lower live electrode; means extending downward through said opening of said upper live electrode to support said intermediate electrode; means for introducing an emulsion into said lower treating space; and means for establishing electric fields in both said upper and said lower treating spaces.

HAROLD C. EDDY.
